UNITED STATES PATENT OFFICE.

RALPH BAGGALY, OF PITTSBURG, PENNSYLVANIA.

LOADING APPARATUS.

SPECIFICATION forming part of Letters Patent No. 746,253, dated December 8, 1903.

Application filed April 23, 1903. Serial No. 153,944. (No model.)

To all whom it may concern:

Be it known that I, RALPH BAGGALY, of Pittsburgh, Allegheny county, Pennsylvania, have invented a new and useful Loading Apparatus, of which the following is a full, clear, and exact description, reference being had to the accompanying drawings, forming part of this specification, in which—

Figure 1 is a plan view of my device, showing in dotted lines the car and the loading-arm in one of its operative positions. Fig. 2 is a side elevation, partly broken away. Fig. 3 is a cross-section on the line III III of Fig. 2, on a larger scale than Figs. 1 and 2. Fig. 4 is a detail side elevation of the delivery-chute and registering mechanism; and Fig. 5 is a front elevation of the delivery-chute, showing the tilting trough.

My invention relates to a loading apparatus for receiving and distributing pigs of copper and like articles to box-cars or cars of other types as well as vehicles of various descriptions without the necessity of employing manual labor.

My apparatus effects the easy and rapid loading of cars with copper pigs or like articles which are difficult to handle manually owing to their weight, shape, and size, but are evenly distributed and properly placed by my improved apparatus upon the car-floor or other place where it is desired to deposit them.

This apparatus is preferably one unit of a complete system which I have devised for handling copper or other ores, their resulting mattes, slags, &c., and the handling of the pigs which are produced by the various processes employed; and it is especially adapted to be used in conjunction with an automatic warehousing-machine invented by me, from which it directly receives the stored pigs and distributes them in proper position upon the car to be loaded.

My invention provides an apparatus which may be placed at one side of the track and stands in such a position that the delivery-arms may reach both ends of the cars and when a box-car is used may be advanced and retracted through the car-door opening. The apparatus also provides for the automatic registration of each pig as it passes from the conveyer by which it is brought to

the loading apparatus. It also provides an alarm-signal by which the operator is apprised of the fact that a predetermined number of pigs have been received and distributed.

Referring now to the drawings, Fig. 1, 2 represents the end of a belt conveyer, which preferably is inclined upwardly a sufficient degree to enable the chute 3 to deliver the pigs or like articles to the curved downwardly-inclined chutes 4 at such an elevation that they will slide by gravity to the delivery-arm 5, Fig. 2. This arm, as shown in Fig. 3, consists of a frame or box-like structure composed of side plates 6 and tie-plates 7. The bottom tie-plate is cut away at 8, Fig. 2, so as to afford a discharge-opening through which the pigs may be discharged after a predetermined number have passed out at the open free end 9, as shown in Fig. 2.

The arm 5 is preferably horizontal and is provided with a floor 10, upon which the pigs slide, suitable wearing-strips 11 being provided to support it and side guides 12 for keeping it in the proper position, as shown in Fig. 3.

At intervals in the floor 10 I provide doors which are hinged at 14, Fig. 2, and are normally held elevated by a hook 15, which engages a pin or rod 16, secured to an arm 17, which is pivoted to the side plates 6 or some other suitable place on the frame.

The arm 17 is connected to the door 13 by 85 a link 18, and when the parts are in the position shown in full lines in Fig. 2 all the doors 13 are rigidly upheld and the pigs will be discharged at the end 9 of the arm 5, the conveyer 19, Fig. 3, being provided with wheel-supported cross-bars 20, which are guided by angles 21 and engage the ends of each pig. As the pigs pass along the arm they engage a finger 22, mounted on a shaft 23, which at one end is provided with an arm 24, to which 95 is secured a pawl 25, Fig. 2, which engages a ratchet-wheel 26, mounted on a shaft 27, and upon its face it is provided with a pin or lug 28, Fig. 3, which at the proper time engages an arm 29, pivoted to the frame of the distributing-arm 5, and having an arm 30 preferably formed integrally therewith, which operates a rod 31, secured to a rock-arm 32, Fig. 2, mounted on a shaft 33, to which the

hook 16 is secured. When the pin 28 moves the arms 29 and 30, the rod 31 and the rock-arm 32 disengage the hook 15 from the rod or pin 16, and the arm 17 drops, and the door 13 falls into the position shown in dotted lines in Fig. 2, and the next succeeding series of pigs or a predetermined number of pigs pass through the opening in the floor 10, formed by the dropping of the door. The other doors 10 13 are operated in like manner and by similar operative connections, the only difference being that three of the doors 13 are operated by a pin 34, located on the large gear 35, which is rotated by the small pinion 36, secured 15 to the shaft 27, which carries the ratchet-wheel 26, the small pinion being rotated as the ratchet-wheel is moved, and at the same time the large gear 35 is slowly moved; but the doors are all released after the full number 20 of pigs which it is intended shall be placed at one end of the car have passed the arm 22.

The arm 5 is supported by a suitable overhead trolley 37, Fig. 2, which is arranged to 25 run on tracks or beams 38, so as to be moved into position to distribute the pigs or other articles or to be retracted so as to be out of the way when the cars are moved into and out of position to be loaded or taken away, as 30 shown in Fig. 1.

After one end of the car is filled the trough 4', Fig. 5, is tilted so as to fill the other end of the car. This is done by the operator, as hereinafter described. The chute 4 is disconnected at 4^a, Fig. 1, from the arm 5, which has just been used, and it is moved out and another arm is brought into position to fill the opposite end of the car. The chute 4 of this arm is secured at 4^a to that portion of the 35 chute carried by the traveling arm 5, which has just been moved into position, and at a given signal the conveyer 2 is started again, and the pigs are delivered and distributed, as before described, only at the opposite end of 40 the car.

As the pigs are delivered by the conveyer 2 to the chute 3 they pass over the finger 39, Fig. 5, and each pig moves the ratchet-wheel 40, Fig. 4, one tooth, and this wheel in turn 45 rotates the pinion 41, which meshes with the gear-wheel 42, which carries a pin 43. As the last pig of a predetermined number—for example, a car-load or a certain consignment—engages the arm 39 the pin 43 engages the 50 arm 44 on the shaft 45, which shaft carries the arm 46, connected to a rod 47, which operates a hook 48 to disengage it. The hook normally rests under a bracket-arm 49, Fig. 5, secured to the support for the chute 3. 55 This hook 48 retains the tilting-trough portion 4' of the chute 4 in the position shown in full lines in Figs. 4 and 5 until withdrawn by the mechanism just described, the trough-section having been placed in the full-line position by the operator pulling the rod 50, and when the other end of the car has been loaded

with the desired number of pigs or other articles a spring acts to tip the trough-section in the opposite direction when the hook is retracted, and this only takes place when the 70 car has received its full complement of pigs. The same movement that trips the hook operates the cord 51, Fig. 4, and sounds an alarm 52, showing that another car is needed, or the signal may be used for any other purpose desired. The conveyer 19, Fig. 1, may be operated by suitable gear connection 53 54, driven by any suitable power.

By the apparatus above described a certain number—say twenty-five pigs of a total car-load of three hundred pigs—are first delivered in a pile at the end of the distributor. The ratchet mechanism on the passage of the first twenty-five pigs will open the door 13 nearest the outer end of the distributor, so that the second group of twenty-five pigs will be delivered in a pile nearer the middle of the car. In like manner the other doors will be opened in regular sequence until one hundred and fifty pigs have been distributed in six piles 90 over one half of the car-floor. Then another distributing-arm is introduced and six piles are distributed in like manner over the other half of the car-floor.

The advantages of my invention will be 95 apparent to those familiar with the difficulties experienced in the handling of metal pigs and like articles, since by the use of this apparatus much time and labor are saved, and the apparatus being simple in construction is reliable and not likely to get out of order, and when not in use it may be moved out of the way so that no obstruction is afforded to the movement of the cars into and out of position.

Many variations in the mechanical construction of this device will suggest themselves to the skilled mechanic, and changes in the form and arrangement of the parts may be made without departing from my invention.

I claim—

1. A loading device for cars having a distributor movably supported and adapted to be moved into position to extend over the car-floor, a positively-driven conveyer adapted to carry articles along the same, and means 115 for discharging the articles at various parts of the distributor; substantially as described.

2. A loading device for cars having an elevated source of supply, a chute, a distributor adapted to extend over the car-floor, a positively-driven conveyer adapted to carry articles along the same, and means for discharging the articles at various parts of the distributor; substantially as described.

3. A loading device for cars having a distributor adapted to extend over the car-floor, a positively-driven conveyer adapted to carry articles along the same, openings in the bottom portion of the distributor provided with closing devices, and mechanism arranged to 125 release said devices automatically; substantially as described.

4. A loading device for cars having a distributor adapted to extend over the car-floor, a conveyer adapted to carry articles along the same, means for discharging the articles at various parts of the distributor, and an alarm actuated after the passage of a certain number of articles; substantially as described.

In testimony whereof I have hereunto set my hand.

RALPH BAGGLEY.
